(57) **CLAIM**

We claim the ornamental design for a draft stopping device, as shown.

DESCRIPTION

FIG. 1 is a perspective view of the draft stopping device of the present invention;

FIG. 2 is a front elevational view of the draft stopping device of the present invention;

FIG. 3 is a top view of the draft stopping device of the present invention;

FIG. 4 is a rear elevational view of the draft stopping device of the present invention;

FIG. 5 is a bottom view of the draft stopping device of the present invention;

FIG. 6 is a side elevational view of the draft stopping device of the present invention; and,

FIG. 7 is a side elevational view of the draft stopping device of the present invention.
